UNITED STATES PATENT OFFICE.

EMIL TAEGE, OF ARLINGTON HEIGHTS, ILLINOIS.

DESIGN FOR A MILK-WARMING PAN.

SPECIFICATION forming part of Design No. 30,503, dated April 4, 1899.

Application filed February 23, 1899. Serial No. 706,588. Term of patent 7 years.

To all whom it may concern:

Be it known that I, EMIL TAEGE, a citizen of the United States, residing at Arlington Heights, in the county of Cook and State of Illinois, have invented and produced a new and original Design for a Milk-Warming Pan; and I do hereby declare the following to be a full, clear, and exact description of the invention, such as will enable others skilled in the art to which it appertains to make and use the same.

In the drawings, Figure 1 is a perspective view of the milk-warming pan. Fig. 2 is a plan view of the milk-warming pan. Fig. 3 is a longitudinal section taken on the line xx in Fig. 2.

As shown in the drawings, the leading features of the design consist of an oblong pan provided with partitions arranged lengthwise of the pan and having openings at their ends arranged alternately and an inclined false bottom extending in zigzag form between the partitions and the sides and ends of the pan and having an outlet at its lower end a little above the lowest part of the false bottom.

A is the oblong pan, which is provided with rings a' , projecting above its sides, which rings constitute the means for lifting it. The pan A has partitions B arranged longitudinally of

it and having openings b at one end. The 30 openings b are arranged alternately, one partition having its opening at one end and the other at its other end.

B' are longitudinal bars which extend over the tops of the openings and connect the ends 35 of the partitions with the ends of the pan.

C is an inclined false bottom supported in the pan and extending in zigzag form between the bottom edges of the partitions and the sides and ends of the pan. This false 40 bottom has a continuous inclination or slope from one end to the other, and c is an outlet-pipe at its lower end, which projects through one end of the pan a little above the false bottom.

D is an inlet for the hot water, and d is an outlet for the same, projecting from one end of the pan.

I claim—

The design for a milk-warming pan, substantially as herein shown and described.

In testimony whereof I affix my signature in presence of two witnesses.

EMIL TAEGE.
